UNITED STATES PATENT OFFICE.

ALBERT MATHEWS, OF NEW YORK, N. Y.

ATTACHMENT FOR AIR-SHIPS.

No. 870,448.

Specification of Letters Patent.

Patented Nov. 5, 1907.

Application filed March 16, 1907. Serial No. 362,643.

To all whom it may concern:

Be it known that I, ALBERT MATHEWS, a citizen of the United States, and a resident of the city of New York, borough of Brooklyn, in the county of Kings and State of New York, have invented a new and Improved Attachment for Air-Ships, of which the following is a full, clear, and exact description.

This invention is designed to be applied to air ships having suitable propelling and steering mechanism, and has for its object to provide mechanism simple and light in structure and effective in operation, for the purpose of elevating the device to which it is applied.

In the accompanying drawings, which illustrate my invention in its preferred form, Figure 1 is a side elevation of a device embodying my invention applied to a main frame; and Fig. 2 is a plan of the same.

As illustrated in the drawings, 1 represents a platform having a rail 2 extending around the edge thereof, and a motor 3 of any suitable construction supported on said platform. The motor is provided with a driving shaft 4 upon which are mounted beveled gears 5 meshing with corresponding gears 6 attached to the lower ends of upright shafts 7, which shafts are supported in bearings formed on cross bars 8 and 9 respectively, attached to standards 10. Radial arms 11 are mounted upon the upper ends of the shafts 7, and provided on their outer ends with buckets each having a curved wall 12 extending in a quarter circle, and sector ends 13. The buckets may be mounted upon the radial arms 11 in any suitable manner, but as shown herein the arms extend through the oppositely dis-

posed end walls of each of the buckets so as to combine strength and lightness in said parts. When the device is in use the drive shaft 4 rotates the vertical shafts 7, the radial arms 11, and the buckets mounted thereon. 35 The buckets are driven against and gather in the air as they move forward and exert a downward pressure on the air by reason of their curved top and back, thereby causing the machine to be lifted and supported by the upward re-action of the air to an extent proportionate to the resistance of the forward motion of the buckets. The device may be applied to air ships of any suitable construction having any desired means for propelling and steering the machine.

Having thus described my invention, what I claim 45 as new and desire to secure by Letters Patent is:

1. An air ship attachment comprising a plurality of buckets rotatable in a horizontal plane, and provided with curved walls extending in a quarter circle, and similar oppositely disposed sector ends. 50
2. An air ship attachment comprising a plurality of buckets having curved walls extending in a quarter circle and similar oppositely disposed sector ends mounted upon horizontally rotating arms. 55
3. An air ship attachment comprising vertically arranged rotating shafts provided with radial arms, and a plurality of buckets having oppositely disposed sector ends secured to said arms, and curved walls extending in the arc of a circle.

In testimony whereof I have signed my name to this 60 specification in the presence of two subscribing witnesses.

ALBERT MATHEWS.
